ADJUSTABLE BAND

Filed Aug. 5, 1922

UNITED STATES PATENT OFFICE.

KNUT E. ENGLUND, OF BROOKLYN, NEW YORK, ASSIGNOR TO ROBERT H. GAY, OF NEW YORK, N. Y.

ADJUSTABLE BAND.

Application filed August 5, 1922. Serial No. 579,906.

To all whom it may concern:

Be it known that I, KNUT E. ENGLUND, a citizen of the United States, and residing at Brooklyn, in the county of Kings and 5 State of New York, have invented certain new and useful Improvements in Adjustable Bands, of which the following is a specification, such as will enable those skilled in the art to which it appertains to make and use 10 the same.

This invention relates to adjustable bands and particularly to devices of this class designed for use in securing suitably flexible or other tubings in connection with suitable 15 supports, and the object of the invention is to provide a device of the class specified which is so constructed as to permit of the mounting of said band in connection with a suitable support by hand, and by the use 20 of a suitable tool, such as a screw driver, when excess pressure is required; a further object being to provide improved means for retaining the separate parts or end portions of the band together and for reinforcing and 25 strengthening one end portion of the band; and with these and other objects in view the invention consists in a band of the class and for the purpose specified which is simple in construction, efficient in use, and which is 30 constructed as hereinafter described and claimed.

The invention is fully disclosed in the following specification, of which the accompanying drawing forms a part, in which the 35 separate parts of my improvement are designated by suitable reference characters in each of the views, and in which:—

Fig. 1 is a transverse sectional view through a flexible tubing mounted on a suitable support, and indicating the method of 40 mounting one of my improved bands thereon.

Fig. 2 is a view similar to Fig. 1 but showing the parts in a different position.

45 Figs. 3 and 4 are plan views of the construction shown in Fig. 2 viewed from different angles.

Fig. 5 is a sectional detail view of one end portion of a modified form of band which I 50 may employ.

Fig. 6 shows a plan and sectional view of one end portion of another modified form of band; and,

Fig. 7 shows a plan and sectional view of

one end portion of still another modified 55 form of band.

The invention shown and described herein is an improvement on that shown and described in a patent granted to me on the 2nd day of May, 1922, No. 1,414,731 in which a 60 tool of specific construction was employed for coupling the end portions of the band together. The present invention relates to a band of the class under consideration which is so constructed as to avoid the necessity of 65 the use of a specific tool and in connection with which a screw driver or similar tool may be used for the purpose of securing the end portions of the band together.

For the purpose of illustrating one use 70 of my improvement, I have shown in Figs. 1 to 4, a part of a pipe 10 on which is mounted a rubber tubing or hose 11 which is secured on the pipe by one of my improved bands 12. In the construction shown in Figs. 1 to 75 4 inclusive, the band 12 comprises two ring members 13 closed or joined at one end as shown at 14 and said end portion of the band is provided with a plurality of spaced teeth or projections 15, which are substantially 80 arc-shaped in form in cross section and which are formed by providing a number of transverse cuts in the band 12 or the end portion 14 thereof, and pressing one edge of said end portion adjacent to each cut 85 outwardly to form the teeth or projections 15. It will be noted that the teeth or projections 15 are joined to the body of the end portion 14 of the band through sections of substantially the same area as the width of 90 said teeth or projections to form a strong and durable projecting member. The other end portions of the ring members 13 are open and are joined and reinforced by a transverse plate or clip member 16 preferably of greater thickness than the material 95 employed in the band 12 and the end portions of the ring members 13 are secured to the plate or clip member 16 by welding, riveting, or in any other desired manner.

100 The plate or clip member 16 is provided with a downwardly or inwardly directed and preferably pointed lip or flange 17 which overlaps the ends of the ring members 13, and the lip or flange 17 is adapted to interlock with the teeth or projections 15 to securely hold the end portions of the band together. The plate or clip member 16 is 105

also provided with an upwardly or outwardly directed part 18 which forms a finger piece to facilitate the attachment of the band to a suitable support by hand, and to 5 also form a bearing against which a suitable tool may be placed and operate in moving the plate or clip member into position to engage the teeth or projections 15.

It will also be noted that the end portion 10 14 of the band is provided with projecting members 19 which are adapted to extend beneath the other end portion of the band or the ring members 13 to form a continuous annular compression body of said band, 15 when mounted on a suitable support, and the members 19 are preferably slightly tapered.

In the use of my improved band 12 as shown in Figs. 1 to 4 inclusive, it will be 20 noted that the band is applied to the tubing 11 by hand, which result is accomplished by pressure of the thumb upon the projecting part 18 of the member 16 and if stronger pressure is required for securely sealing the 25 connection between the tubing 11 and the pipe 10, a screw driver or other tool is placed beneath the member 16 and in engagement with one of the teeth or projections 15 beneath such member as shown in Fig. 1 of the 30 drawing, after which the screw driver or other tool is moved to the right to advance the end portion of the band 12, provided with the member 16, longitudinally of the other end portion thereof so that the lip or 35 flange 17 will engage another tooth or projection as illustrated in Fig. 2 of the drawing and this operation will be repeated until the band 12 has been securely wrapped around the tubing 11. In order to remove 40 the band, all that is necessary to do is to place a screw driver or other tool beneath the end portion of the band provided with the clip member 16 to pry the same upwardly and the end portions of the band will 45 then spring apart.

In Fig. 5 of the drawing, I have shown a slight modification of the construction shown in Figs. 1 to 4 inclusive in which I substitute for the plate or clip member 16, 50 a similar part 20 which is formed integral with the end portion of the band by folding said end portion backwardly upon the band, and fashioning the folded part 21 to form a lip 17 similar to the lip 17 in Figs. 1 and 55 2 of the drawing, and the part 18 is formed from the free end portion of the band. In this construction, the band 12 is also made solid instead of being provided with the separate ring member 13, and an aperture 22 60 is provided in the band in juxtaposition to the part 18 to permit of the insertion of a screw driver or other tool. The other end portion of the band will be of the same construction as shown in Figs. 1 to 4 inclusive.

65 In Fig. 6 of the drawing, I have shown

another modification in which the part 18 is formed by cutting a section 23 from a solid band and bending it upwardly and downwardly and this operation forms an aperture 24 in the band in juxtaposition to 70 the part 18, the same as in Fig. 5 of the drawing. With this construction, the free end portion of the band is bent downwardly to form the lip or flange 17.

The construction shown in Fig. 7 is practically the same as that shown in Fig. 6 75 with the exception that the part 18 is formed by pressing or fashioning the material of the band outwardly to form said part and in this construction, an aperture 25 is also 80 provided in juxtaposition to the part 18, and the free end portion of the band is provided with a lip 17 as in Fig. 6 of the drawing.

In all of the forms of construction shown, 85 the part 18 of the band serves as a finger piece and backing against which a suitable tool may operate in mounting the band in a suitable support, and this structure also serves to reinforce and strengthen the band 90 at this point and it will be noted that the parts 18 in Figs. 6 and 7 of the drawing will be riveted, welded or otherwise secured together. It will be noted that my invention 95 is not necessarily limited to the specific use herein set out as the same may be used for many other purposes and constructed of lighter or heavier material, depending upon the use to which the band is to be adapted and while I have shown certain details of 100 construction for carrying my invention into effect, it will be noted that I am not necessarily limited to these details and various changes therein, and modifications thereof 105 may be made within the scope of the appended claims without departing from the spirit of my invention or sacrificing its advantages.

Having fully described my invention, 110 what I claim as new and desire to secure by Letters Patent, is:—

1. A unitary sheet metal band of the class described, one end portion of which is provided with a plurality of spaced projecting elements and the other end portion of the band being provided at its end with an inwardly projecting lip formed from the material of said band and adapted to pass over the projecting elements on the other end portion of the band, and to engage one of 115 said elements for securing said end portions together.

2. A unitary sheet metal band of the class described, one end portion of which is provided with a plurality of spaced projecting elements and the other end portion of the band being provided at its end with an inwardly projecting lip formed from the material of said band and adapted to pass over 120 the projecting elements on the other end por- 125

- tion of the band, and to engage one of said elements for securing said end portions together, and said band being provided adjacent to the last named end portion thereof 5 with an aperture through which a suitable tool may be passed for moving said last named end portion longitudinally of the other end portion of the band.
3. A unitary sheet metal band of the class described, one end portion of which is provided with a plurality of spaced projecting elements and the other end portion of the band being provided at its end with an inwardly projecting lip formed from the material of said band and adapted to pass over the projecting elements on the other end portion of the band, and to engage one of said elements for securing said end portions together, and said last named end portion 15 of the band being provided with an outwardly projecting part by means of which said end portion may move longitudinally of the other end portion.
4. A unitary sheet metal band of the class described comprising a metal strip, one end portion of which is provided with a plurality of spaced projecting teeth formed by pressing predetermined portions of the strip outwardly and the other end portion of the 20 strip being provided with an integral inwardly projecting lip adapted to engage the projecting teeth on the other end portion of said strip.
5. A unitary sheet metal band of the class described comprising a metal strip, one end portion of which is provided with a plurality of spaced projecting teeth formed by pressing predetermined portions of the strip outwardly, and the other end portion of the 25 strip being provided with an inwardly projecting lip adapted to engage the projecting teeth on the other end portion of said strip, and said last named end portion of the band being provided with an outwardly projecting integral part.
6. A unitary sheet metal band of the class described comprising a metal strip, one end portion of which is provided with a plurality of spaced projecting teeth formed by pressing predetermined portions of the strip outwardly, and the other end portion of the strip being provided with an inwardly projecting lip adapted to engage the projecting teeth on the other end portion of 30 said strip, and said last named end portion of the band being provided with an outwardly projecting part, adjacent to which said end portion of the strip is apertured.
7. A unitary sheet metal band of the class described comprising a metal strip, one end portion of which is provided with a plurality of spaced projecting teeth formed by pressing predetermined portions of the strip outwardly, and the other end portion 35 of the strip being provided with an inwardly projecting lip adapted to engage the projecting teeth on the other end portion of said band, said lip forming a space 40 between the end portions of said band into which a suitable tool may be placed to engage one of said teeth to advance the last named end portion of the band longitudinally of the other end portion thereof.
8. A band of the class described, one end portion of which is provided with a plurality of spaced projecting teeth formed by pressing predetermined portions of the band outwardly, and the width of said teeth being substantially the same throughout their length, and the other end portion of the band being provided with an inwardly projecting lip adapted to engage the projecting teeth on the other end portion of said band.
9. A band of the class described, one end portion of which is provided with a plurality of spaced projecting teeth formed by pressing predetermined portions of the band outwardly, and the width of said teeth being substantially the same throughout their length, and the other end portion of the band being provided with an inwardly projecting lip adapted to engage the projecting teeth on the other end portion of said band, said lip forming a space between the end portions of said band into which a suitable tool may be placed to engage one of said teeth to advance the last named end portion of the band longitudinally of the other end portion thereof.
10. A band of the class described, one end portion of which is provided with a plurality of spaced projecting teeth formed by pressing predetermined portions of the band outwardly, and the width of said teeth being substantially the same throughout their length, and the other end portion of the band being provided with an inwardly projecting lip adapted to engage the projecting teeth on the other end portion of said band, said lip forming a space between the end portions of said band into which a suitable tool may be placed to engage one of said teeth to advance the last named end portion of the band longitudinally of the other end portion thereof.
11. A band of the class described, one end portion of which is provided with a plurality of spaced projecting teeth formed by pressing predetermined portions of the band outwardly, and the width of said teeth being substantially the same throughout their length, and the other end portion of the band being provided with an inwardly projecting lip adapted to engage the projecting teeth on the other end portion of said band, said lip forming a space

- between the end portions of said band into which a suitable tool may be placed to engage one of said teeth to advance the last named end portion of the band longitudinally of the other end portion thereof, and said last named end portion of the band being provided with an outwardly projecting part, adjacent to which the band is apertured.
- 10 12. A band of the class described, one end portion of which is provided with a plurality of spaced projecting teeth formed by pressing predetermined portions of the band outwardly, the other end portion of the band being provided with an inwardly projecting lip adapted to engage the projecting teeth on the other end portion of said band, and said last named end portion of the band being provided with an outwardly projecting part, adjacent to which the band is apertured.
- In testimony that I claim the foregoing as my invention I have signed my name this 2nd day of August, 1922.

KNUT E. ENGLUND.
